DISPOSABLE ABSORBENT PAD FOR
DIATHERMY APPLICATORS

Cecil J. Birtcher, Alhambra, Calif.

Application May 11, 1940, Serial No. 334,557

1 Claim. (Cl. 128—413)

This invention relates to disposable absorbent pads and pertains more particularly to a disposable absorbent pad for a diathermy applicator.

In short wave diathermy treatment the short wave treatment field is applied to the area to be treated by means of applicators which have treatment faces of insulating material to prevent electrical contact with the patient. For sanitary reasons it is not desirable to place these insulating faces in contact with a patient's body. Thus it has been the practice to cover such applicator with a clean towel or other pad each time it is used so that the patient is in contact with a sanitary surface.

There is also another reason that a pad of absorbent material such as a towel has been used to cover the treatment face of the applicator. The short wave energy usually produces sufficient heat to induce perspiration on the treated surface, the lack of ventilation at the area of contact of the applicator accelerating such condition, so that there is a tendency for droplets of perspiration to form. The local currents set up in these droplets produce sufficient heat to produce skin burns. Thus the absorbent pad prevents the formation of droplets and burns.

The use of towels or the like for absorbent pads is generally expensive. Furthermore, the resultant applicator is bulky and does not appear neat and professional. In some instances, when small applicators are used as in the treatment of the head portions, it is not practicable to use such bulky pads.

It is, therefore, a particular and important object of the invention to provide an inexpensive, compact and effective disposable absorbent pad which is adapted to be removably secured to the treatment face of a short wave diathermy applicator.

Other objects of the invention will be set forth in the following description of certain preferred embodiments thereof, or will be apparent from such description.

The accompanying drawing illustrates such embodiments, and referring thereto:

Fig. 1 is a face view of a pad according to my invention applied to the treatment face of a diathermy applicator, the constituent layers of the pad being progressively broken away to illustrate the construction;

Fig. 2 is a sectional view of the pad taken along line 2—2 in Fig. 1, the applicator being shown in elevation;

Fig. 3 is a sectional detail of a portion of the pad taken along line 3—3 in Fig. 1;

Fig. 4 is a view of the back face of a pad illustrating a modified form of means for securing it to an applicator;

Fig. 5 is a sectional view thereof taken along line 5—5 in Fig. 4;

Fig. 6 is a view of the back face of a pad illustrating a further modified form of construction;

Fig. 7 is a sectional detail thereof taken along line 7—7 in Fig. 6; and

Fig. 8 is a sectional detail illustrating a form of construction which is alternative to that illustrated in Figs. 6 and 7.

15 Referring to Figs. 1—3 of the drawing, the pad structure is shown as comprising an absorbent layer 1 of paper for example, having its rearward face adhesively secured to a supporting layer 2, of relatively stiff paper for example.

20 The pad is preferably shaped to conform with the applicator on which it is to be used. The pad is shown as generally oval shaped to fit an oval applicator 3. The applicator usually consists of a casing of insulating material containing a conductive electrode and is shown provided with suitable insulated terminal means 4 extending from the rear face thereof for the conduction of

short wave energy thereto.

25 The actual shape and construction of the electrode does not form a part of this invention since my pad construction is generally independent of the electrode construction. However, by way of example I have shown an electrode such as used in the "caput" applicator which forms the subject matter of my copending application Serial No. 333,508 filed May 6, 1940.

30 Attaching means for securing the absorbent layer to the applicator are provided, such as rubber bands or the like 5 and 6 disposed at the rearward face of the supporting layer 2 and held in position with respect thereto through the agency of an attachment layer 7 which is adhesively secured to the support layer 2. The attachment layer 7 is preferably recessed in its

35 plane adjacent the edges where the bands extend from the pad as at 8 to minimize the tendency for the attachment layer to tear at its edges or pull away from the support layer when the rubber bands are stretched about the applicator as shown in Figs. 1 and 2.

40 It is not always necessary or desirable that the attaching means such as the rubber bands be placed parallel to one another at longitudinally spaced positions as shown in Fig. 1. The placement of such attachment means depends to con-

siderable extent on the shape of the applicator on which the pad is to be used. An example of a pad for use with a circular applicator is illustrated in Figs. 4 and 5.

Referring thereto, the pad is shown as comprising a circular absorbent layer 10 having a supporting layer 11 of relatively stiff or rigid material adhesively secured thereto. The attachment means is shown as comprising rubber bands 12 and 13 which are secured to the supporting layer by means of an attachment layer 14 which is adhesively attached to the supporting layer. The rubber bands are arranged transverse to one another with the band 12 encircled by the band 13. The layer 14 extends through the loop of each of the bands. This layer is preferably recessed as at 15 near the edge of the pad where the bands emerge, as with the form illustrated in Fig. 1.

In Figs. 6 and 7 a form of pad construction is illustrated with which the attachment layer is omitted. Referring to said figures, the pad is shown as comprising an absorbent layer 20 adhesively secured to a supporting layer 21. The attachment means, comprising one or more rubber bands 22, is secured between the absorbent layer and the supporting layer and encircles the supporting layer. In order to keep the front surface of the layer 22 smooth and thus minimize the chance of having perspiration droplets form on the skin of the patient, the supporting layer is provided with a channel 23 to receive the band 22. This channel may be formed by pressing a groove in the member 21. The ends of the channel are preferably recessed as at 24 to relieve strains incident to stretching the band when the pad is attached to an applicator.

In Fig. 8 an alternative form of construction is illustrated. As with the form illustrated in Figs. 6 and 7, a band 22a encircles a supporting layer 21a and is secured between an absorbent layer 20a and the supporting layer 21a. In this case, however, the supporting layer is smooth and a channel 23a is formed in the absorbent layer. This may be done since the absorbent layer is usually sufficiently soft to have a channel pressed therein by compression without destroying the smooth surface contour of the front face of the absorbent member. A suitable absorbent layer may comprise a plurality of connected layers of the soft paper commonly used to remove makeup from the face.

Alternative forms of pad construction will doubtless appear to those skilled in the art, and I do not choose to be limited to the examples delineated herein, but rather to the scope of the 20 subjoined claim.

I claim:

25 A disposable pad adapted to be secured to the face of an electrode member of a short-wave diathermy applicator consisting of a relatively rigid flexible insulating supporting layer, an insulating attachment layer adhesively secured to one surface of said supporting layer, a plurality of insulating elastic bands, a portion of each band being secured between said supporting 30 layer and said attachment layer, and the remainder of each band being adapted to encircle said electrode member and to hold said attachment layer elastically in contact with the face of said electrode member, and a pad of insulating absorbent material secured to the other surface of said supporting layer.

35 CECIL J. BIRTCHER.
